(57) **CLAIM**

I claim the ornamental design for a pool skimmer oil absorber, as shown and described.

DESCRIPTION

FIG. 1 is a perspective view of a pool skimmer oil absorber, showing my new design;

FIG. 2 is a top plan view of FIG. 1;

FIG. 3 is a bottom plan view of FIG. 1;

FIG. 4 is a right-side elevational view of FIG. 1, the left-side elevational view being a mirror image thereof;

FIG. 5 is a front elevational view of FIG. 1; and,

FIG. 6 is a rear elevational view of FIG. 1.

The broken lines showing a mouse face in the figures depict environmental matter and form no part of the claimed design.
